UNITED STATES PATENT OFFICE

PHILIP L. MCKEE, OF CHICAGO, ILLINOIS

GREENHOUSE CONSTRUCTION

Application filed March 26, 1928. Serial No. 264,826.

My invention relates to the construction of greenhouses and particularly to the manner of providing ventilating openings for the inclined roofs of the greenhouses. The present application relates to improvements in the construction shown in my co-pending application, Serial No. 240,987, filed December 19th, 1927.

As set forth in said application, in the present-day greenhouse construction it is the practice to provide a number of greenhouse units side by side to cover a given area of ground. These greenhouses are formed with substantially inclined roofs which converge upwardly to a point directly over the central longitudinal portion of the greenhouse and transverse of the width thereof. In the prior constructions these upwardly converging roofs are provided with outwardly opening ventilating windows which extend in opposite directions from each side of the ridge pole, so that when these outwardly extending windows are opened fresh air is admitted at the top portion of the greenhouse. In addition each greenhouse of heretofore existing construction has been provided along its vertical lateral walls and in some instances along the lower portions of its upwardly inclined glass roofs, with heating pipes for the purpose of heating the air which goes through these ventilating windows on each side of the ridge pole which are opened for that purpose.

Up to the present time it has been the universal practice when providing a plurality of these greenhouse units to arrange them side by side; thus, for instance, where it was desired to provide two of these greenhouse units to double the capacity of a single greenhouse unit, the two were arranged side by side, and each unit was provided with two oppositely extending and outwardly opening windows on each side of the ridge pole.

One of the objects of my present invention is to provide an arrangement of ventilating doors or windows on each side of the crown or ridge pole of the roof of the greenhouse wherein such plurality of windows

may be opened and closed independently of each other as distinguished from my aforementioned application wherein the windows were arranged in interconnected relation and in a manner such that one of the windows could not be opened without opening the other.

In another phase of my invention, another object is to provide a construction wherein one of the windows over-lappingly lies upon a shiftable portion of the other window, the construction being such as to permit the alternate sash to pivotally slide along the superimposed sash of the other window so that while the two windows are arranged in overlapping closed relation, the alternate window may be swung to open position without disturbing the over-lying window.

These and other objects of my invention will be apparent from a perusal of the following specification when taken in connection with the accompanying drawings, wherein:

Figure 1 is a side view, partly in section, of my enlarged greenhouse unit provided with the novel arrangement of double ventilating windows on each side of the ridge pole;

Figure 2 is a top plan view of the same with certain parts broken away;

Figure 3 is an enlarged detail view of the construction showing independently operated windows; and

Figure 4 is a modified view showing another form of construction.

It has heretofore been common practice in the construction of greenhouses to place two single units side by side, each of said units comprising vertical side walls and upwardly inclined roofs converging to ridge poles. The heating means consisting of steam pipes or hot water pipes are usually placed along these vertical walls and possibly along the lower portion of the upwardly inclined roofs which are formed of glass so as to permit the passage of the sun's rays and light therethrough.

In these single unit constructions two windows are mounted on each side of the ridge pole and are hinged to said ridge poles so

as to open outwardly. When closed, these windows overlie the upper free edges of the roof so as to close these ventilating openings on the side of the ridge poles. It will be noted that in these single units the roofs are relatively close to the top of the vertical walls and that due to this fact it is not possible to provide more than two of such windows which may be opened to permit the ingress of fresh air. This is due to the fact that if additional windows were provided in the upwardly inclined roofs of the single unit construction the fresh air when entering would be brought directly into contact with the growing vegetation at points relatively close to the upper end of the wall, and which entering air would not have a chance to be heated by the steam pipes.

In my improved construction which is shown in full lines in Figs. 1 and 4 of the drawings, I construct my enlarged greenhouse unit by forming the vertical side walls 22 of the same height as the heretofore existing single units, and I arrange these vertical walls 22 in spaced apart relation and distance so as to cover double the amount of ground area heretofore enclosed by these vertical walls in a single unit.

However, in my improved and enlarged construction the upwardly inclined roofs 24 and 26 are extended beyond the height of the usual ridge pole of the single unit to a point wherein the ridge pole 28 of my improved construction is disposed considerably above the height of the ridge pole of a single unit, but not twice the height. I preferably support this ridge pole 28 and the beam forming the upwardly inclined roofs 24 and 26 by means of the usual cross truss beams and central poles 30 carried by the laterally disposed supports 31 extending at sufficient intervals longitudinally of the inclined roofs. It will be noted that in my enlarged or double unit construction the ridge pole 28 is approximately four times the height of the vertical wall height 22.

The support 30 is preferably an I-beam and has riveted at its upper end a cross piece 32, to the opposite portions of which are riveted the upper ends of the roof supporting I-beams 24 and 26 respectively. In addition at the top of the cross piece 32 and between the ends of the beams 24 and 26 and immediately on top of the support 30, I rivet a second cross support 34 which has riveted to it and mounted thereon a metallic I-beam extending longitudinally of the greenhouse. This I-beam constitutes a part of the ridge pole and supports the ridge pole cap 36. The details of construction of this I-beam 28 and ridge pole cap 36 and the manner of supporting all the window ventilating sashes therefrom, while disclosed herein are not claimed since they form the

subject matter of a separately formed application concurrently pending herewith.

At a point substantially the length of the inclined roof beams 24 and 26, I rivet to the under side thereof a preferably metallic cross beam 38 which forms a support for the stationary window sash 40 and in which is mounted the usual transparent pane 42 which sash or a multiple number of sashes extend downwardly in inclined formation to the top of the vertical wall 22. Extending transversely of the plurality of inclined roof beams 24, I mount an angularly shaped metal beam 43 as by means of rivets and to this beam, I bolt a riveted L-shaped beam 45 which constitutes a support for a wooden spacing block or cross beam 47 which extends transversely of the inclined roof. The construction of my present application differs from that of my former and co-pending application in that instead of hinging the lower sash 49 of one of the windows to the stationary sash 40, I hinge such sash as at 50 to this stationary beam 47 so that the sash 49 underlies the beam 47 and is positioned when closed substantially opposite the vertical sash of the inverted L-shaped beam 45. The free or outer end of the sash 49 rests freely upon the top surface of the window sash 40. Suitable mechanism is employed for swinging this window sash 49 to outward or open position as shown in dotted lines and this mechanism comprises a lever 52 pivoted as at 54 to a relatively short arm 56 attached to the outer end of the sash 49. The inner end of lever 52 is pivoted as at 58 to an arm 60 mounted on a rotatable shaft 62 mounted on a bracket 64 on the inclined roof beam 24 whereby on rotation of the shaft 62 the levers 52 and 60 will be moved to open dotted line position as shown.

The upper window sash 66 is pivotally mounted as by means of the hinge 68 in a manner similar to that shown in my former application, the hinge 68 being secured preferably to the vertical side of the ridge pole cap 36 and the inner portion of the sash 66 being arranged to rest under this ridge pole cap and against the T-shaped beam 28. This sash is opened by a similar system of levers comprising the relatively long lever 70 pivoted as at 72 to a short bracket 74 carried by the outer portion of the sash and the inner end of this lever 70 is pivoted as at 76 to a shorter lever 78 rigidly mounted on a turnable shaft 80 carried on a bracket 82 from the inclined beam 24. The outer or free end of the sash 66 overlies freely the top surface of the stationary cross beam 47 and the arrangement is such that the upper window 66 may be opened independently of the lower window 49. It will be seen that when the lower window is open the hinges at the point 50 will swing to open position without disturbing the upper window. This con-

struction is brought about by reason of the spacing block 47.

In the construction shown in Figure 4, I mount upon the inclined roof beam 24 a cross beam or channel beam 84 and one portion of the hinge 86 is suitably bolted to the upper vertical flange 88 of this cross beam 84 while the other portion of the other flange 90 of the hinge is suitably fastened to the 10 sash 92 of the lower window so that this window is free to swing about the pivot 94 of the hinge. However, in this construction, the upper portion of the sash 92 is provided with an up-standing rounded, hump-like 15 projection 96 upon which freely lies the outer portion of the sash 98 of the upper window. This upper window is hinged to the crown of the ridge pole in exactly the same manner as shown in Figure 3 herein. In this 20 modified form of construction, by reason of the rounded hump-like portion 96, the lower sash 92 is free to open and close while leaving the upper sash 98 in undisturbed position and this is due to the rounded portion 25 which forms a rolling pivot for forming a contact between the lower and upper sashes. It will be seen that this latter forms a very economical, simple, yet effective construction for permitting two window sashes 30 to be opened and closed independently of one another.

Having thus described my invention, what I claim as new and desire to secure by Letters Patent is:

35 1. In a greenhouse construction, the combination of upwardly inclined roof beams converging to the ridge pole, stationary window sashes mounted on said inclined roof beams at the lower portion of the inclined 40 roofs on each side of the ridge pole, and a plurality of pivotally mounted windows for opening and closing the space between said stationary windows and the ridge pole on each side of the ridge pole, comprising a 45 stationary beam carried by said inclined roof members and lying transversely thereacross, a lower window sash hinged to said roof beam and adapted to swing outwardly, the outermost portion of said sash overlapping 50 and overlying the topmost portion of said stationary window sashes, and a second shiftable window sash pivotally mounted adjacent the ridge pole and having the free end of said sash overlying the hinged portion of 55 said first mentioned sash, and operating means for opening said window sashes.

2. In a greenhouse construction, the combination of roof beams inclined upwardly and converging to a ridge pole construction, 60 stationary window sashes mounted on said roof beams for covering the lower portion of the inclined roofs, and two pivoted windows mounted on said roof and lying between the uppermost portion of the station- 65 ary window sashes and the ridge pole on

each side thereof, one of said windows being hinged adjacent the ridge pole and the other of said windows being hinged adjacent the outer end of said first mentioned window, said windows being arranged in overlapping relation, and means for opening said windows independently. 70

3. In a greenhouse construction, the combination with the vertical walls of the greenhouse and the upwardly inclined roof beams 75 and the ridge pole construction at the convergence of said roof beams, a plurality of stationary window sashes covering the lower portions of said inclined roof beams, a transversely disposed beam located substantially 80 intermediate the distance between the upper portions of said stationary sashes and the ridge pole, a stationary spacing block mounted on said transverse beam, a lower window hinged to said block and adapted to open 85 outwardly, the outer portion of said window sash being adapted freely to overlie the stationary window sash and a second window having its sash hinged to the ridge pole structure and having its outer sash freely 90 overlying said block and means for opening and closing said windows independently. 95

4. In a greenhouse construction, the combination of the vertical side walls of the greenhouse and the upwardly inclined roof 100 beams and the ridge pole construction at the convergence of said roof beams, a cross beam mounted on said roof beams, a spacing block rigidly mounted on said cross beam, a window sash pivoted substantially at the bottom portion of said spacing block, and adapted to swing outwardly, means for opening and closing said window sash, the upper portion of said stationary block constituting a stop or abutment, a second window sash 105 hinged at the ridge pole and the outer end of said window sash overlying said stationary block and disposed so as to permit the first mentioned window sash to swing to open position without contacting the outer portion of said second window sash, and means for independently opening and closing said second window sash. 110

5. In a greenhouse construction, the combination of the upwardly inclined roof beams and the ridge pole construction at their convergence, a cross beam mounted on said roof beams, a first window sash hingedly mounted upon said cross beam so as to permit said window sash to swing outwardly to 115 open position, a support section positioned adjacent the hinged end of said window sash and extending upwardly therefrom, and a second window sash hinged adjacent the ridge pole with the other end thereof lying 120 freely on said upwardly extending portion, and means for independently opening and closing said window sashes. 125

6. A ventilating construction for the roof of a greenhouse comprising two window 130

sashes hingedly mounted upon roof members, an upwardly projecting section extending along and adjacent the hinged end of one of said sashes, the other of said sashes 5 having its free end overlying said upwardly extending section, the construction being such as to permit the underlying sash to swing freely about its hinge to open position without effecting the movement of the free 10 end of the overlying sash resting upon the upwardly extending section.

7. In a greenhouse construction, the combination of roof beams inclined upwardly and converging to a ridge pole construction, 15 stationary window sashes on said roof beams for covering the lower portion of the inclined roofs, and two pivoted windows mounted on said roof and lying between the uppermost portion of the stationary window 20 sashes and the ridge pole, one of said windows being hinged to a fixed position adjacent the ridge pole and the other of said windows being hinged in a fixed position adjacent the other end of said first mentioned 25 window, said windows being arranged in overlapping relation, and means for opening said windows independently.

In witness whereof, I have hereunto subscribed my name.
